UNITED STATES PATENT OFFICE.

ANDREW C. MOLHOLT, OF KENOSHA, WISCONSIN.

DESIGN FOR A WATCH-CHARM OR SIMILAR ORNAMENT.

49,096.

Specification for Design.

Patented May 23, 1916.

Application filed March 8, 1916. Serial No. 82,936. Term of patent 14 years.

To all whom it may concern:

Be it known that I, ANDREW C. MOLHOLT, a subject of the King of Denmark, residing at Kenosha, in the county of Kenosha and State of Wisconsin, have invented a new, original, and ornamental Design for Watch-Charms or Similar Ornaments, of which the following is a specification, reference being had to the accompanying drawing, forming part thereof.

The figure is a plan view of a watch charm showing my new design.

I claim:

The ornamental design for a watch charm or similar ornament as shown.

ANDREW C. MOLHOLT.
